(57) **CLAIM**

The ornamental design for a collapsible four-door crab trap, as shown and described.

DESCRIPTION

FIG. 1 is a perspective view of a collapsible four-door crab trap, showing my new design;

FIG. 2 is a side elevation view thereof;

FIG. 3 is an end elevation view thereof;

FIG. 4 is a top plan view thereof;

FIG. 5 is a bottom plan view thereof; and,

FIG. 6 is a perspective view showing the collapsible four-door crab trap in a collapsed state.

The broken lines shown in FIGS. 1-5 are provided for showing the collapsible four-door crab trap in its environment and form no part of the design.
